UNITED STATES PATENT OFFICE.

THOMAS A. McGINLEY, OF PITTSBURGH, PENNSYLVANIA, ASSIGNOR TO THE DUFF MANUFACTURING COMPANY, OF PITTSBURGH, PENNSYLVANIA, A CORPORATION OF PENNSYLVANIA.

JOURNAL-BUSHING FOR JACKS.

1,220,991.

Specification of Letters Patent. Patented Mar. 27, 1917.

Application filed September 23, 1916. Serial No. 121,738.

To all whom it may concern:

Be it known that I, THOMAS A. McGINLEY, a citizen of the United States, residing at Pittsburgh, Allegheny county, Pennsylvania, have invented a new and useful Improvement in Journal-Bushings for Jacks, of which the following is a full, clear, and exact description, reference being had to the accompanying drawings, forming part of this specification, in which--

Figure 1 is a side elevation of one form of jack, to which I have applied one form of my invention.

Fig. 2 is a detail sectional view, on the line II-II of Fig. 1, showing one of the bushings in position, and the other bushing ready to be applied.

Fig. 3 is a perspective view of one of the bushings.

Fig. 4 is a perspective view of the spring key for securing the bushing in position, and

Fig. 5 is a detail sectional view of another form of socket lever.

This invention relates to an improvement in bearings for jack socket levers, and is designed to provide means for readily and securely retaining the socket lever journal bushings in position in the jack frame.

The precise nature of my invention will be best understood by reference to the accompanying drawings, which will now be described, it being premised, however, that various changes may be made in the details

of construction of the several parts, without departing from the spirit and scope of my invention as defined in the appended claims.

Referring to the accompanying drawings, the reference character 2 designates a jack frame having side extensions 3 for the bearings for the socket lever. 4 designates the lifting bar, which is provided with the usual ratchet teeth, and which are arranged to be engaged by a pawl 5 connected to a socket lever 6. The socket lever 6 is provided with trunnions 7 which are journaled in bushings 8 seated in openings 9 in the extensions 3 of the jack frame. The extensions 3 of the jack frame are also provided with recesses 10 on the inner faces thereof, as well as key seats 11. These key seats 11 are arranged to receive spring keys 12, which engage one wall of the seat and a flat portion 13 on the

bushings 8. The keys are also provided with an upwardly extending projection 14 arranged to engage the edge of the key seats at the inside thereof, to retain the key in position within the seat, and which will in turn retain the bushings 8 in position.

The socket lever is first slipped into position by passing the trunnions downwardly through the recesses 10, and the bushings 8, together with the spring keys, are then slipped into position. The legs of the keys are compressed by means of suitable pliers sufficiently to permit the extensions 14 to pass under the walls of the key seats.

When it is desired to remove the bushings, the projection or extension 14 is engaged and depressed by means of a screw driver, and the pressure applied thereto will not only compress the spring members, but will also tend to force the keys outwardly. After the keys have been removed the bushings can readily be withdrawn from their seats, so that the socket lever can be removed from the frame.

In Figs. 1 and 2 I have shown a socket lever having integral trunnions 7, while in Fig. 5 I have shown a socket lever having a through shaft which forms the trunnions 7a.

The advantages of my invention result from the provision of a spring key for retaining a journal bushing in position with relation to the jack frame and the socket lever.

I claim:

1. A jack frame having socket lever bearings, removable bushings adapted to be seated in said bearings to form bearings for the socket lever journals, each of said bushings having a key seat, there being a key seat in each of the bearings parallel with the axes of the socket lever journals, a spring key for retaining each bearing in position, each of said keys having two legs, one of said legs being arranged to engage the key seat on the bushing and the other being arranged to engage the key seat in the bearings in the frame, substantially as described.

2. A jack frame having socket lever bearings, removable bushings adapted to be seated in said bearings to form bearings for the socket lever journals, each of said bushings having a key seat, there being a key

seat in each of the bearings parallel with the axes of the socket lever journals, a spring key for retaining each bearing in position, each of said keys having two legs, 5 one of said legs being arranged to engage the key seat in the bearings in the frame, and an angular projection on one of the legs for engaging the edge of the key seat in the bearing frame, the end of the other leg being 10 arranged to engage the end wall of the key seat on the bushing, substantially as described.

3. A jack frame having socket lever bearings, bushings seated therein and arranged 15 to form bearings for the journals of the socket lever, each of said bushings having a key seat on the periphery thereof, there be-

ing a key seat in each of the bearings of the frame extending parallel with the axis of the bearings from the ends thereof, and a 20 U-shaped spring key for each bushing, the legs of said key extending parallel with the axes of the bearings, the end of one of said legs engaging the end wall of the seat on the bushing, and a projection on the end of 25 the other leg for engaging the inner edge of the seat in the frame, substantially as described.

In testimony whereof, I have hereunto set my hand.

THOMAS A. McGINLEY.
